4 Claims. (Cl. 33—205)

This invention relates to the art of drilling boreholes into subsurface formations by the rotary drilling method and, more particularly, relates to the art of detecting, ascertaining, and indicating deviations from vertical of a borehole drilled by said method.

In the drilling of boreholes by the rotary drilling method, the equipment employed includes a drill bit which is mounted on the lower end of a string of drill pipe, the drill pipe being provided at its upper end with a Kelly rod by means of which the drill pipe is rotated through the medium of a rotary table. While the drill pipe is rotated in the borehole for the purpose of deepening the borehole, it is common practice to circulate a drilling fluid continuously through the drill stem and drill bit. This drilling fluid is pumped downwardly inside the drill pipe through the eyes of the bit and upwardly in the annular space between the drill pipe and the borehole walls.

During the drilling of the borehole by the rotary drilling method, it is often difficult to maintain a vertical course. Because deviations from the vertical, if of any appreciable magnitude, cause many difficulties, it has been the practice to survey the borehole from time to time to determine whether or not the borehole is deviating from the vertical and to determine the extent of the deviation, if any. Many different devices have been suggested for use for the aforementioned purpose although most of these devices have been found to be impractical in one or more respects. Some of these devices are equipped with a valve which is adapted to close off the central passage extending through the drill pipe for the making of a determination as to the inclination of the borehole; no means are provided for opening this valve after the determination has been made and, accordingly, the drill stem must be removed from the hole while it stands full of drilling mud. Disadvantages which attend to such a practice are obvious.

It is an object of the present invention to provide a device adapted to determine and to indicate the degree of inclination of a borehole from the vertical. It is a further object of the present invention to provide such a device equipped with valve means which can be locked in the open position to permit the pulling of a dry drill string.

The aforementioned objects and other advantages of my invention will be apparent from the following detailed description taken in conjunction with the accompanying drawings. In the drawings like numerals indicate like parts throughout.

Fig. 1 is a view in partial elevation of the device of the present invention when normal circulation of drilling fluid is maintained and the device is held in an open position;

Fig. 2 is a view similar to that of Fig. 1 but with circulation of drilling fluid stopped and the device assuming a closed position;

Fig. 3 is a detailed sectional view of the device shown

in Figs. 1 and 2, but with the device locked in an open position by a retrievable go-devil;

Fig. 4 is a sectional view of the lower portion of the device shown in Fig. 3;

5 Fig. 5 is a sectional view taken along the line 5—5 of Fig. 3;

Fig. 6 is a view taken along the line 6—6 of Fig. 4; and

10 Fig. 7 is an enlarged detail view of a portion of the device shown in Fig. 4.

Referring to the drawing, numeral 10 designates a section of drill string and preferably is a drill collar sub. An inwardly projecting shoulder 11 is provided with drill pipe 10 preferably a short distance above the lower 15 end of the drill stem at the point at which it is attached to a drill bit, not shown. The device of my invention is shown in Fig. 1 as it would normally be positioned within a drill pipe 10.

The device of my invention includes a housing 12, 20 preferably tubular, as shown, which may be formed of a series of sections joined by screw threads as at 13. Affixed to the upper extremity of housing 12 is a spear 14 to which may be attached a wire line, not shown, for lowering or raising the device in drill pipe 10. Housing 12 adjacent its upper end defines a closed chamber 15 with a pendulum 16 suitably suspended from the upper 25 end thereof. So that pendulum 16 may readily attain a vertical position at all times, upper bearing 17 and lower bearing 18 are provided and held in place against pendulum 16 by means of locking ring 19. Also positioned within chamber 15 is a detector piston 20 defining step-wise recess 21 in its upper surface. Step-wise recess 21 in reality consists of a series of concentric recesses of decreasing diameter designated as 21a, 21b, 21c, and 30 21d forming a series of ledges designated by numerals 21e, 21f, 21g, 21h, and 21i. The lower end of chamber 15 is closed by means of packing gland 22 defining opening 23 extending vertically therethrough. Opening 23 is provided with an annular groove 24 adapted to receive 35 sealing means, such as an O-ring 24'.

Housing 12 also defines a second chamber, this chamber being designated by the numeral 25. Mounted within housing 12 and forming the upper end of chamber 25 is piston 26 carrying sealing ring 27 on its outer periphery, 40 piston 26 being adapted to be moved longitudinally within housing 12 in fluid-tight relation with the walls thereof. Partition 28 constitutes the lower wall of chamber 25. Extending vertically through partition 28 are three separate openings designated by the numerals 29, 30, and 31 and shown in greater detail in Fig. 7. The passage of fluid downwardly through opening 29 is prevented by one-way or uni-directional flow valve 32 consisting of a ball 33 biased downwardly against the valve seat by spring 34. Opening 31 is closed by means of a frangible disc 37 held in place by retaining nut 38. Screw-threaded into opening 30 is orifice plate 36 provided with bidirectional flow orifice 36'. Frangible disc 37 is provided as a safety feature so that if orifice 36' should become plugged, disc 37 will rupture, permitting fluid to escape from chamber 25. The size of orifice 36' is related to the dimensions of step-wise piston 20 in a manner which will be described hereinafter.

Spaced beneath partition 28 and screw-threaded to housing 12 is plug 39 defining central passage 40 extending vertically therethrough. Attached to plug 39, as at 41, is a distensible, resilient bag 42 which may suitably be made of rubber.

Affixed to housing 12 above its lower end by means of brackets 44 is a sealing member 43. On its outer cylindrical surface sealing member 43 carries a suitable sealing means 45 which may suitably be chevron packing. The

lower edge 46 of sealing member 43 is adapted to abut upon shoulder 11 carried by drill pipe 10 in which event sealing means 45 provides a fluid-tight seal between member 43 and drill pipe 10.

Mounted at the bottom 12' of housing 12 is sleeve valve 54, which is adapted to move slidably on the exterior of housing 12 in fluid-tight relation therewith as a result of the seal provided by sealing member 53 which may suitably be an O-ring. The outer dimension of sleeve valve 54 is such that it just passes thru the inside of sealing member 43, the outer surface of sleeve valve 54 and the inner surface of member 43 being adapted to cooperate to prevent or to retard materially the passage of fluid therebetween; in other words, a fluid-tight seal here is not essential. A nesting cage 54' for valve 54 may be provided.

Affixed to the upper end of slide valve 54 is a valve actuating member which may suitably be a plurality of rods 60 extending upwardly along housing 12 and freely past the centering fins 62. Rods 60 terminate above centering fin 62 and they may be connected as by means of a ring 63. Rods 60 are connected by means of a yoke 64 to piston rod 26', screw 65 securing yoke 64 to piston rod 26'.

Step piston 20 and piston 26 are connected together for movement in concert by means of piston rod 26', piston rod 26' extending through opening 23 of packing gland 22 in fluid-tight relation therewith, sealing means 24' providing the seal.

It will be noted that the lower end 12' of housing 12 is open so that the exterior surface of resilient bag 42 is exposed to the drilling fluid which fills the central opening of drill pipe 10. It is also essential that the upper surface 26a of piston 26 be exposed to the fluid inside drill pipe 10. In the device shown in Fig. 1 access by the drilling fluid is had to the upper surface 26a of piston 26 through slot 70 in housing 12. This arrangement is essential so that there is a pressure differential between the upper surface 26a of piston 26 and the exterior surface of bag 42. It is also essential that a biasing means, such as spring 72, be provided for biasing piston 26 upwardly within housing 12, the bias exerted by the biasing means being less than the pressure differential between the drilling fluid adjacent the upper surface 26a and the drilling fluid surrounding bag 42.

In the drawing the space between wall 28 and plug 39 is shown as being connected with the space between the packing gland 22 and step piston 26 by means of a conduit 75. This conduit or similar connection is not essential and may be omitted entirely. If, however, a conduit such as conduit 75 is provided, step piston 20 is then provided with a passage 76 which connects the space between step piston 20 and packing gland 22 with recess 21 of piston 20. If a conduit 75 is provided, chambers 15 and 25 are both filled with a hydraulic fluid, conduit 75 permitting the fluid pressure in each of these chambers to be equalized. Filling of these chambers is accomplished by removing plug 9 in the upper part of chamber 15. Irrespective of whether chamber 15 is filled with fluid and fluidly connected with chamber 25 by means of conduit 75, chamber 25 and bag 42, together with the interconnecting spaces, are filled with fluid. Filling should be accomplished when piston 26 is in its uppermost position and when bag 42 is in its undistended state.

In use the device of my invention operates in the manner hereinafter described.

After the drill bit attached to the lower end of drill pipe 10 has been placed on bottom, the device of my invention is inserted in drill pipe 10 at the surface of the earth and pumped downwardly therein until shoulder 46 of sealing member 43 abuts on shoulder 11 of drill pipe 10. While drilling fluid is being circulated downwardly within drill pipe 10 and upwardly through the annular space between drill pipe 10 and the walls of the borehole, the pressure differential between bag 42 and upper surface

26a of piston 26 as a result of circulating fluid forces piston 26 to its lowermost position as is best illustrated in Fig. 4. Inasmuch as slide valve 54 is mechanically connected to piston 26 through rods 60, yoke 64, and piston rod 26', slide valve 54 is also in the full down position. Piston 26 and slide valve 54 remain in the full down position so long as circulation is continued.

When circulation of drilling fluid is discontinued and there is no differential pressure across this device, spring 10 72 is the only effective unbalanced force operating on the device of my invention and causes piston 26 to move upwardly and slide valve 54 to move into the central opening in sealing member 43. If the borehole does not deviate from the vertical, the detector step piston 20 will 15 move upwardly within chamber 15 until the lower end of pendulum 16 strikes the bottom of recess 21i, thus preventing further upward movement of step piston 20 and piston 26. If however, the borehole is inclined from the vertical, the lower end of pendulum 16 will 20 strike on ledge 21e, 21f, 21g, or 21h of recess 21, the particular ledge involved depending upon the degree of departure of the borehole from the vertical. Of course, the amount by which piston 26 is permitted to move will depend upon the particular ledge upon which the lower 25 end of pendulum 16 abuts.

The operator can determine which of the aforementioned ledges the lower end of pendulum 16 has abutted upon by applying to the drilling mud within drill pipe 10 a predetermined pressure and then promptly shutting off the pumps by which this pressure was attained. This pump pressure acts on the upper surface 26a of piston 26 forcing piston 26 downwardly within chamber 25. The rate at which piston 26 moves downwardly is determined by the rate at which fluid can be displaced from chamber 25 into resilient bag 42 through orifice 36'. The size of orifice 36' has been preselected so that the time required to displace fluid from chamber 25 into bag 42 is inversely proportional to the slope of the borehole. The time which the operator would measure for 40 determining the slope of the borehole would be the period from the initial pump pressure built up until the pump pressure drops off suddenly.

Check valve 32 is provided in order that orifice 36' may be by-passed when piston 26 is moving upwardly 45 so that chamber 25 can be filled quickly and easily. Frangible disc 37 is provided as a safety feature in the event that orifice 36' should become plugged, the frangible disc being rupturable by applying pump pressure to the drilling fluid inside drill string 10.

50 Prior to removing drill string 10 from the borehole, a go-devil 100, shown in Fig. 3, is introduced into the hole for locking slide valve 54 in the open position so that drilling fluid can drain out the lower end of drill string 10 and the string removed dry from the hole. Go-devil 55 100 is provided at its upper end with a spear 101 and a downwardly depending skirt 102. It is also provided with a plurality of latching dogs 103 normally pressed downwardly and inwardly by a biasing means, such as spring 104. The lower edge 105 of skirt 102 is arranged 60 to contact ring 63, pushing said ring and the rods 60 attached thereto downwardly. Inasmuch as rods 60 are attached to slide valve 54, slide valve 54 is also held in the full down open position so that drilling fluid located thereabove can flow therewith and out the lower end 65 of the drill string. Springs 104 bias dogs 103 inwardly so that the upper edge 106 of these dogs engages with the lower edge 14' of spear 14 when go-devil 100 is raised. It will be understood, of course, that go-devil 100 may be raised by means of a wire line attached to spear 101.

70 It will be appreciated that various changes may be made in the device of my invention without departing from the spirit thereof.

What I wish to claim as new and novel and to secure by Letters Patent is:

75 1. A borehole slope indicator for use in a tubular

member positioned in said borehole, comprising, in combination, a housing including a first closed chamber and a second chamber; a pendulum suspended in the upper end of said closed chamber so as to hang vertically at all times; a piston in said closed chamber arranged for longitudinal movement in said chamber having a stepwise recess in its upper surface capable of receiving the lower end of said pendulum; a piston in said second chamber arranged for longitudinal movement in said chamber in sealing contact with the walls forming said chamber, the upper surface of said piston being exposed to fluids surrounding said housing; a spring biasing upwardly the piston in said second chamber; a piston rod connecting the piston in said first closed chamber with the piston in said second chamber, said piston rod being adapted to pass in and out of said first closed chamber in fluid-tight relation, with the walls forming said chamber; a sealing member affixed to said housing and adapted to fit sealably in said tubular member, said sealing member defining flow space therethrough; a valve element mounted on the lower end of said housing mechanically connected to said pistons for simultaneous movement therewith, said valve element being adapted to move in and out of the flow space through said sealing member for opening and closing completely said flow space to the passage of fluid therethrough upon each downward and upward movement, respectively, of said pistons; and a distensible reservoir defining an enclosed chamber in fluid communication through stationary openings of selected size with said second chamber, the outer surface of said distensible reservoir being exposed to the fluid located below said sealing member in said tubular member.

2. A borehole slope indicator for use in a drill pipe through which drilling fluid may be circulated under pressure comprising, in combination, a housing defining a first chamber vertically spaced above and longitudinally aligned with a second chamber; a pendulum suspended adjacent the closed upper end of said first chamber; a first piston arranged for longitudinal movement in said first chamber having a recess in its upper surface consisting of a series of concentric circular ledges, the diameter of which decreases as the depth of the recess increases; a second piston arranged for longitudinal movement in said second chamber in sealing tight relation with the walls of the housing forming said chamber, the upper surface of said second piston being exposed to said drilling fluid; a spring biasing said second piston upwardly in said second chamber; a piston rod connecting together said first and second pistons, said piston rod being adapted to pass in and out of said first chamber in fluid-tight relation with the housing forming said chamber; a sealing member affixed to said housing and adapt-

ed to be positioned within said drill pipe in fluid-tight relation therewith, said member defining a flow space extending vertically therethrough; a sleeve valve mounted on the lower end of said housing below said sealing member, said sleeve valve being adapted to be moved longitudinally on said housing in fluid-tight relation therewith for opening and closing the flow space through said sealing member; a valve actuating member affixed to said valve and extending along said housing to a point adjacent the upper end thereof, said actuating member also being affixed to said piston rod for movement in unison with said rod; a distensible, resilient bag defining an enclosed chamber in fluid communication through an orifice with said second chamber, the outer surface of said bag being exposed to the drilling fluid located below the contact area between said sleeve valve and said sealing member.

3. A device as defined in claim 1 wherein said stationary openings comprise a bi-directional flow orifice, a uni-directional flow valve orifice and a normally closed frangible safety orifice.

4. A borehole slope indicator for use in a well pipe comprising a longitudinally extending housing positioned in said pipe, a pendulum suspended in said housing adapted to assume a vertical position, longitudinally movable detector means arranged in said housing adapted to be moved downwardly by the action of circulating fluid, means connected to said detector means adapted to urge said detector means upwardly, the upward movement of said detector means being limited by said pendulum, a sealing member arranged on said housing in fluid-tight relation to said pipe, said member defining a flow space extending vertically therethrough, a valve element mounted on the lower end of said housing in fluid-tight engagement therewith and connected to said detector means for longitudinal movement therewith, said valve element opening and closing completely the flow space through said sealing member upon each downward and upward movement, respectively, of said detector means, stationary bi-directional fluid flow control means arranged in said housing adapted to control downward movement of said detector means in order to determine deviations of the borehole from the vertical, and distensible means, the interior thereof fluidly communicating with said fluid flow control means and the outer surface thereof being exposed to fluid located in said pipe.
